(57) **CLAIM**

The ornamental design for a mattress pad overlay, as shown and described.

DESCRIPTION

FIG. 1 is a top perspective view of the mattress pad overlay. FIG. 2 is a top view of the quilt which is identical to a bottom view of the mattress pad overlay.

FIG. 3 is a right side view of the quilt which is identical to a left side view of the mattress pad overlay; and,

FIG. 4 is a bottom side view of the quilt which is identical to a top side view of the mattress pad overlay.

The broken lines represent stitching and form part of the claimed design.
